UNITED STATES PATENT OFFICE.

WALTER D. STOCKLY, OF FAIRMONT, WEST VIRGINIA.

RAILWAY CROSSTIE.

1,410,082.

Specification of Letters Patent. Patented Mar. 21, 1922.

Application filed April 5, 1921. Serial No. 458,704.

To all whom it may concern:

Be it known that I, WALTER D. STOCKLY, a citizen of the United States, and a resident of the city of Fairmont, in the county of Marion and State of West Virginia, have invented certain new and useful Improvements in Railway Crossties, of which the following is a specification.

My invention relates to railway cross-ties 10 and more particularly to ties adapted for use in mine railways.

It is the object of my invention to provide a tie of this general type which comprises a small number of parts thereby 15 eliminating unnecessary bolts, nuts, pins, etc., which are liable to become loosened and separated from the tie and subsequently lost.

To this end, the invention comprises a U-shaped channel member forming the body 20 of the tie. Adjacent each end of the tie body I provide a clip or lug and spaced from each of these an abutment adapted to cooperate with a wedge for securing the rail to the tie.

25 An important feature of my invention resides in the construction of this abutment whereby the wedge for securing the rail to the tie is easily put into operation and thereafter prevented from working loose. The bearing face for the wedge is made convex thereby facilitating the insertion of the wedge between the abutment and the rail, the wedge thereafter becoming seated upon the abutment by reason of the engagement of 30 the convexed face of the abutment with the wooden wedge.

The various features of my invention will be made more apparent in the accompanying specification and drawings in which:

40 Fig. 1 is a longitudinal sectional view of one end of the tie constructed in accordance with my invention.

Fig. 2 is a plan view of the structure illustrated in Fig. 1.

45 Fig. 3 is a fragmentary perspective view showing more in detail the abutment, and

Fig. 4 is a section on line 4—4 of Fig. 1.

The numeral 10 represents the tie which is formed of an inverted U-shaped channel member made preferably of rolled steel. This tie is adapted to support the rail 11 having a web portion 12 and a base or flange 13.

Disposed adjacent each end of the tie is 50 a clip or lug 14 also formed preferably of a U-shaped channel member secured to the tie

by a rivet or bolt 15. One end of each clip is inclined upwardly as shown at 16, away from the tie thereby providing a wedge shaped space 17. This wedge shaped space 60 is adapted to receive a flange 13 of the rail.

Disposed also at each end of the tie 10 and spaced from each lug 14 is an abutment or clip 18 secured to the tie by suitable rivets or bolts 19.

One portion of this abutment 20 projects upwardly and is inclined so as to form with the base portion an obtuse angle. The portion 20 of the abutment is arched or bent to form a convex bearing face 21. A wooden 70 wedge 22 is adapted to be inserted between the rail and the portion 20 of the abutment, thereby bearing against this convex bearing surface 21. Because the ends of the convex members flare outwardly or away 75 from the rail, the insertion of the wedge between the abutment and the rail is facilitated. When the wedge has been inserted between the abutment and the rail, the pressure of the convex bearing face upon the 80 wedge tends to seat the wedge against this abutment by forming a depression therein, thereby preventing a displacement of the wedge with respect to the other part of the tie.

The abutment 18 need not be as wide as the tie 10 and therefore the tie may be constructed of a width suitable for the type of rail which it is designed to carry and an abutment of this width secured thereto. In 90 this latter instance, the abutment will function with the wedge in the same manner as described hereinbefore.

In assembling the ties and rails, the flange 13 of the rail is disposed under the upwardly inclined end 16 of the lug 14 and within the wedge shaped space 17 formed by inclining the end 16 of the lug away from the tie. The wedge 22 is then inserted between the rail and the abutment, the wedge bearing 100 against the web 12 of the rail on one side and against the convex face 21 of the abutment on the other side. The pressure exerted upon the rail by the wedge tends to move the rail sidewise and into its position under the 105 lug 16, the flange 13 of the rail being securely wedged in the wedge-shaped space 17. A vertical displacement of the wedge 22 is prevented by the inclination of the portion 20 of the abutment.

When the track is in use the stress imparted to the rails tends to tip them out.

wardly in a direction away from the center of the track. This stress upon the rails is positively resisted by the lugs 14 which are disposed nearer the center of the track and 5 bear against the half of the rail flange which would tend to move upwardly under the aforesigned stresses. The stresses tending to tip the rails inwardly or toward the center of the track are negligible and are resisted 10 by the contact of the wedge with the outer flange of the rail.

The primary purpose, therefore, of the wedge and abutment is to keep the rail in intimate engagement with its corresponding 15 lug and by the construction illustrated, this is assured.

The parts of the device just described are easily assembled and the rail may be secured to the tie without the use of nuts and bolts 20 or the like, which would raise the possibility of parts becoming loosened and the rail unsecured upon the tie.

Certain modifications of the particular structure illustrated may be resorted to without departing from the spirit and scope of my 25 invention and to this end, I reserve this right.

Having thus described my invention, what I claim is:

30 1. A railway tie comprising a body member, rail engaging lugs secured to said body member adjacent its ends, and separate wedge abutments of substantially L-shape spaced from said lugs whereby wedges may 35 be inserted between said abutments and the rails.

2. A cross-tie for mine railways comprising

ing a body member, rail engaging lugs rigidly secured to said member and in position to engage the flange of rails, convex faced 40 abutments spaced from said lugs and inclined at an angle with respect to the body member and wedges adapted to be inserted between the rail and said abutments, substantially as and for the purpose described. 45

3. A cross-tie for mine railways comprising a body member, rail engaging lugs rigidly secured to said member, cooperating abutments secured to said tie adjacent said lugs, said abutments being each formed with 50 a base and an inclined portion, inclined at an obtuse angle with respect to the base, said inclined portion being curved to form a convex bearing surface and a wedge adapted to be inserted between the rail and said abutment bearing on one hand against the web 55 of said rail and on the other hand against the convexed bearing surface, substantially as for the purpose described.

4. A railway tie comprising a body member, rail engaging lugs secured to said member adjacent its ends, separate abutments of substantially L-shape spaced from said lugs, said abutments being provided with convex bearing faces and wedges adapted to be inserted between said abutments and the rails. 60

5. A railway tie comprising a body member, rail engaging lugs secured to said body member, wedge abutments on each end of said body, said abutments being inclined 70 and having horizontally disposed convex bearing faces and wedges adapted to be inserted between said abutments and the rails.

WALTER D. STOCKLY.
